UNITED STATES PATENT OFFICE.

CLARENCE E. SMITH, OF NEW BRITAIN, CONNECTICUT, ASSIGNOR TO THE
NORTH & JUDD MANUFACTURING COMPANY, OF SAME PLACE.

DESIGN FOR A BUCKLE.

SPECIFICATION forming part of Design No. 30,717, dated May 9, 1899.

Application filed April 15, 1899. Serial No. 713,209. Term of patent 7 years.

To all whom it may concern:

Be it known that I, CLARENCE E. SMITH, a citizen of the United States, residing at New Britain, county of Hartford, State of Connecticut, have invented and produced a certain new and original Design for a Buckle, of which the following is a full, clear, and exact description.

My invention relates to a new and original design for a buckle, and in the illustration thereof shown in the accompanying drawings—

Figure 1 shows my design for a buckle in plan view. Fig. 2 is a reverse side of the same. Fig. 3 is a section of Fig. 1 on the line 3 3.

My design comprises, primarily, a buckle having a looped body portion, of which the rear portion B is substantially straight.

The leading feature of the design resides in the appearance of the reverse side, which, as Fig. 2 shows, is centrally depressed, the bottom of said depression, as at A, being flat. On each side of the flat floor A are raised ribs or beads B, which are substantially parallel with the outline of the looped body portion, excepting the rear portion B.

What I desire to claim and secure by Letters Patent is—

The design for a buckle substantially as herein shown and described.

Signed at New Britain, Connecticut, this 10th day of January, 1899.

CLARENCE E. SMITH.
